Primary Examiner — Wan Laymon*Assistant Examiner* — Clint A Samuel(74) *Attorney, Agent, or Firm* — Knobbe, Martens, Olson & Bear, LLP(57) **CLAIM**

The ornamental design for a storage device blister tray, substantially as shown and described.

DESCRIPTION

FIG. 1 is a front perspective view of a storage device tray, showing my new design;

FIG. 2 is a top plan view thereof; a bottom plan view thereof is an identical image;

FIG. 3 is a front elevation view thereof; a rear elevation view thereof is an identical image;

FIG. 4 is a left side elevation view thereof; and, FIG. 5 is a right side elevation view thereof.

The broken line showing in the drawings is included for the purpose of illustrating unclaimed portions of the storage device blister tray and forms no part of the claimed design.

1 Claim, 2 Drawing Sheets(56)
